UNITED STATES PATENT OFFICE

REMI J. GITS, OF CHICAGO, ILLINOIS

KNIFE

Application filed December 16, 1931. Serial No. 581,393.

This invention relates to knives and more particularly to pocket knives of the type in which the blade is projected longitudinally of a hollow handle, and may be locked in various positions according to the effective length of blade desired.

The main objects of this invention are to provide a simplified and more compact structure for knives of the character described.

10 An illustrative embodiment of the present invention is described in the accompanying drawing in which:

Figure 1 is a perspective view of a complete knife in closed position.

15 Fig. 2 is a side plan view of a knife showing the inner casing and blade, the knife being in open position.

Fig. 3 is a sectional view taken on the line 3—3 of Fig. 2.

20 Fig. 4 is an enlarged sectional view of a complete knife taken as on the line 4—4 of Fig. 2.

Fig. 5 is a side view of the blade.

25 Fig. 6 is a perspective view of the blade locking spring.

Fig. 7 is a perspective view of the forward end of the inner casing.

Fig. 8 is a perspective view of the rear end of the inner casing.

30 Fig. 9 is an enlarged sectional view of a complete knife taken as on the line 9—9 of Fig. 3.

Referring more in detail to the drawing, the knife 1 comprises a finished outer casing 2, an inner casing 3, and a knife blade 4. The blade 4 is provided with a butt or shank 5 and is slideable longitudinally in the inner casing 3. The shank 5 is provided with a longitudinal aperture 6 which is spanned by a bridge or fulcrum 7. The bridge 7 is thinner than the shank so as to provide a depression or groove for the cantilever spring 8 and also to provide a fulcrum therefor.

40 The spring 8 is bowed at 9 where it seats in the groove 10 on bridge 7 and is flush with the upper plane of the shank. The bowed end of the spring interlockingly engages the cut out portion of the shank 5 as shown in Fig. 3 and is therefore flush with the lower face 50 plane of the shank. The other end of the

spring 8 has an interiorly threaded collar 11 set therein to receive the threaded shank of a latch button 12 located for operation by the thumb of the user.

The inner casing 3 is provided with spaced 55 stop recesses 13 and interconnecting slots 14 as shown in Fig. 2. The outer casing 2 has a longitudinal slot 15 in registry with slots 14.

60 In assembling the device, the spring 8 with the screw 12 removed is placed over the bridge 7 of the shank 5 in the manner in which it is shown in Fig. 3, and the blade and spring are then slipped into the inner casing 3 by inserting them through the front end of casing 65 (see Fig. 7). The blade is forced inwardly until the collar 11 slips into one of the recesses 13 and then the latch button 12 is screwed into the collar 11. The outer casing 2 is now applied to the entire unit so that 70 the end opening and the side slot 15 are the only exposed openings. (See Fig. 1.)

75 In operation the latch button is forced inwardly, disengaging the collar 11 from aperture 13. The latch button is now pressed inwardly and moved forwardly for opening the knife, or rearwardly for closing. The recesses 13 act as stops for the collar 11. The effective length of the blade is determined by the user who adjusts it by moving the latch 80 into any one of the recesses 13.

It is to be understood that the cantilever spring 8 constantly urges the collar outwardly and that when the inward pressure is released the spring forces the collar into the 85 first recess it passes and locks it there until the inward pressure is again applied.

Although but one specific embodiment of this invention is herein shown and described, it is to be understood that numerous 90 details of the construction shown may be altered or omitted without departing from the spirit of the invention as defined by the following claims:

95 I claim:

1. A knife comprising a hollow handle, a blade longitudinally slideable in said handle and adapted to be projected beyond one end thereof, said blade having a supporting shank on one end wherein an aperture 100

is provided, said shank having a bridge formed across said aperture, a cantilever spring mounted on said shank and medially fulcrumed on said bridge in said aperture and adapted to frictionally engage the inner wall of said hollow handle, and means for moving said blade longitudinally of said handle.

and for moving said blade longitudinally of said handle.

Signed at Chicago in the county of Cook and State of Illinois this 1st day of December, 1931.

70

REMI J. GITS.

75

2. A knife comprising a hollow handle, 10 a blade longitudinally slidable in said handle and adapted to be projected beyond one end thereof, said blade having a supporting shank on one end and having a longitudinal aperture therein, a cantilever spring mounted on said shank and housed in said aperture, said shank having a fulcrum across said aperture for said cantilever spring, a latch shoulder on said spring, said handle being slotted and provided with a series of stop recesses 20 to engage said latch shoulder, and means for releasing said spring and for moving said blade longitudinally of said handle.

80

3. A knife comprising a hollow handle, a blade longitudinally slidable in said handle 25 and adapted to be projected beyond one end thereof, said blade having a supporting shank thereon, a longitudinal aperture in said shank, a cantilever spring removably mounted on said shank, a fulcrum bridged across said aperture for said spring, the transverse portion of said fulcrum being thinner than said shank to accommodate the thickness of said spring, said shank having a 35 groove in one face to provide a seat for the anchored end of said spring, said spring being completely housed in said aperture and groove flush with the face planes of said shank, a latch shoulder on said spring, said handle being slotted and provided with a series of stop recesses to engage said latch shoulder and means for releasing said spring 40 and for moving said blade longitudinally of said handle.

90

4. A knife comprising a handle having a blade way therein opening through one end thereof, the opposite end thereof being closed, a blade slidable longitudinally in said way and adapted to be projected through the open 45 end of said way, said blade having a supporting shank thereon, a longitudinal aperture in said shank, a cantilever spring removably mounted on said shank, a fulcrum bridged across said aperture for said spring, the transverse portion of said fulcrum being thinner than said shank to accommodate the thickness of said spring, said shank having a groove in one face to provide a seat for the anchored end of said spring, said spring 55 being completely housed in said aperture and groove flush with the face planes of said shank, a latch shoulder on said spring, said handle being slotted and provided with a series of stop recesses to engage said latch shoulder and means for releasing said spring 60
